United States Patent Office

Des. 204,463
Patented Apr. 19, 1966

204,463

CABINET

Gordon A. Thomas and Robert L. Hartley, both %
Harper Ransburg Company, Inc., Indianapolis, Ind.

Filed Nov. 16, 1964, Ser. No. 82,631

Term of patent 14 years

(Cl. D33—19)

FIG. 1.

FIG. 3.

FIG. 2.

FIG. 4.

FIG. 5.

FIG. 6.

FIG. 1 is a perspective view of a cabinet showing our new design;

FIG. 2 is a rear elevation thereof;

FIG. 3 is a top view thereof;

FIG. 4 is a front elevation of a modified form of the cabinet shown in FIG. 1 and differing from the cabinet shown in FIG. 1 in the provision of an additional shelf;

FIG. 5 is a side elevation of the cabinet shown in FIG. 4; and

FIG. 6 is a rear elevation of the cabinet shown in FIG. 4.

The sides of the cabinets opposite the sides shown in FIGS. 1 and 5 are mirror images thereof.

We claim:

The ornamental design for a cabinet, as shown and described.
